CLAIM

(58) **Field of Classification Search**

I claim, the ornamental design for a flat wireless detector for X-ray device, as shown and described.

USPC D24/158–161, 186; D16/250; D14/435,
D14/482

DESCRIPTION

CPC H04N 5/367; G03B 42/04
See application file for complete search history.
